L. C. LOEWENSTEIN.
ELASTIC FLUID TURBINE.
APPLICATION FILED JUNE 22, 1916.

1,240,743.

Patented Sept. 18, 1917.

UNITED STATES PATENT OFFICE.

LOUIS C. LOEWENSTEIN, OF LYNN, MASSACHUSETTS, ASSIGNOR TO GENERAL ELECTRIC COMPANY, A CORPORATION OF NEW YORK.

ELASTIC-FLUID TURBINE.

1,240,743.

Specification of Letters Patent. Patented Sept. 18, 1917.

Application filed June 22, 1916. Serial No. 105,271.

To all whom it may concern:

Be it known that I, LOUIS C. LOEWENSTEIN, a citizen of the United States, residing at Lynn, in the county of Essex, State 5 of Massachusetts, have invented certain new and useful Improvements in Elastic-Fluid Turbines, of which the following is a specification.

The present invention relates to elastic fluid turbines, and particularly to turbines having a conduit leading from an intermediate stage through which motive fluid is adapted to pass. Such a conduit may be for extracting steam for industrial purposes, 10 or for use as an auxiliary exhaust when the turbine is operating non-condensing. In such turbines when operating non-condensing, which means that one or more of the low pressure stages are running idle, there 15 is danger of overheating the last stage wheels which may result in considerable damage. This heating is due to the rotation losses of the wheels continually heating the steam atmosphere surrounding them. This 20 may occur when for any reason the condenser vacuum is lost, as when the operator shuts down the condenser when the unit is 25 working with all the steam extracted in any earlier stage.

30 The object of the present invention is to provide an improved means for obviating this danger, and to this end I provide an automatic arrangement which will insure under all conditions the circulation of elastic 35 fluid through the final stages of the machine when the wheels therein are running idle.

For a consideration of what I believe to be novel and my invention, attention is directed to the accompanying specification and the claims appended thereto.

In the accompanying drawing, Figure 1 is a side elevation partly in section of a portion of an elastic fluid turbine illustrating my invention, and Fig. 2 is a section taken on line 2--2, Fig. 1.

Referring to the drawing, 5 indicates the casing of an elastic fluid turbine and 6 the shaft thereof upon which is mounted the 50 bucket wheels of the machine. In the present instance the machine is shown as being divided into four stages by diaphragms 7, 8 and 9. In the first stage is a wheel 10 having two rows of buckets 11 thereon, and in 55 each of the succeeding stages is a single

wheel 12 having a single row of buckets 13. Elastic fluid is admitted to the high pressure end of the machine by a conduit 14, and after passing through the successive stages exhausts into the head 15 which is connected 60 to a condenser 15^a as is usual. 16 indicates the nozzles through which elastic fluid is admitted to the first stage, and 17, 18 and 19 indicate the nozzles of the remaining stages, which nozzles are located in the diaphragms. 65 Connected to the second stage is a conduit 20 through which elastic fluid may be extracted. This conduit may be for the purpose of connecting the second stage to atmosphere so that the machine may operate 70 non-condensing, or it may be for the purpose of extracting steam for industrial purposes. I preferably provide a ring valve mechanism for controlling the flow of elastic fluid from the second stage to the third, and in 75 the present instance it is shown as comprising a fixed member 21 having openings 22 therein, and a movable member 23 having openings 24. The movable member is adapted to be turned circumferentially to bring 80 the openings 24 into and out of alignment with the openings 22 to regulate the flow of elastic fluid from the second stage to the next succeeding stage. When the machine 85 is used for extracting elastic fluid for industrial purposes, it is desirable to maintain a constant pressure in the extraction stage, and to this end the ring valve is placed under the control of a pressure operated apparatus, which apparatus responds to the 90 pressure existing in the extraction stage. In the present instance, as shown in Fig. 2, the movable member 23 is provided with a gear segment 25 with which engages a short 95 rack 26 connected to the piston 27 of a fluid actuated motor 28. This fluid actuated motor is under the control of a suitable pressure responsive device, in the present instance shown in the form of a diaphragm 29, which is connected to the pilot valve 30 100 of the motor through a bell crank lever 31, rod 32, floating lever 33, and rod 34, the floating lever being connected to the piston rod 35 through an arm 36. The under side of the diaphragm 29 is connected by a suitable pipe 37 to the point at which it is desired to maintain constant pressure, usually 105 to the pipe 20. This forms an ordinary and well known type of a pressure control mechanism for the ring valve, such as is well 110

known, and further details of the structure and operation is believed to be unnecessary. The ring valve when utilized, is so arranged that it can never completely shut off communication between the extraction stage and the next succeeding stage, and to this end one of its openings 22 as indicated at 22^a, Fig. 2, is made larger than the others so that when the ring valve is moved to its final closed position an opening is still left through which a sufficient quantity of elastic fluid may flow from the extraction stage to the succeeding stages to give a circulation, such as will prevent overheating of the wheels running idle in such stages.

However, it may happen that the condenser may fail or is shut down so that the vacuum is lost. Under these circumstances there would not be sufficient difference in pressure between the extraction stage and the final stage to give such a circulation through the final stages as would be required to prevent overheating, and to take care of this I provide a special automatic valve mechanism which will admit elastic fluid at a pressure higher than that of the extraction stage to the final stage or stages of the machine, from which it will circulate backward through the final stages to the extraction stage. This automatic valve mechanism is arranged to be controlled by the pressure in the final stage, or when a stage valve, as ring valve 23 is used, by both the position of the ring valve and the pressure in the final stage, i. e., the condenser pressure, and is such that should the vacuum of the condenser be lost or in the case when a stage valve is used, should it be lost at a time when the stage valve is closed, elastic fluid will be automatically admitted either from a primary source through a reducing valve, or from the first stage, to the final stage or stages of the machine. The condenser vacuum may be lost, for example, due to the condenser being purposely shut down by the operator or due to failure of the apparatus.

In the present instance I have utilized two valves as indicated at 38 and 39, which valves together control the flow of elastic fluid from a primary source through conduit 40 and reducing valve 41, or from the first stage through conduit 42 and non-return valve 43 to the branch conduits 44 and 45 which lead respectively to the two last stages of the machine. The valve 38 is biased toward open position by a spring 46 and is normally held closed by a cam surface 47 on the rack 26 which engages the end of a pin 48, which in turn is connected with an arm 49 pivoted to bracket 50 and upon which the stem of valve 38 rests. When the cam surface 47 moves from beneath the pin 48 the spring 46 opens the valve 38, as best shown in Fig. 2. This occurs when

the ring valve is closed. When the ring valve is open the cam surface 47 engages the pin 48 to close valve 38. The valve 39 is biased toward closed position by a spring 51 and is adapted to be opened by a pressure operated device, here shown in the form of a diaphragm 52 arranged in a casing 53. The casing 53 beneath the diaphragm is connected by a pipe 54 with the exhaust head 70 of the machine. It will thus be seen that the pressure normally existing under the diaphragm 52 is that of the final stage; i. e., the condenser pressure.

During normal operation, when the machine is operating condensing, valve 39 is held closed by the spring 51, such spring being sufficiently strong to seat the valve against the pressure then existing under the diaphragm 52, i. e., the condenser pressure, while the valve 38 may be open or closed according to the position of the ring valve. In any event, so long as the vacuum is maintained there will always be sufficient circulation of elastic fluid through the final stages of the machine to prevent the wheels therein overheating, since the ring valve when closed does not completely shut off the flow of elastic fluid through the final stages. Should, however, the vacuum be lost, the pressure conveyed to the under side of diaphragm 52 by pipe 54 will be such as to open the valve 39 against the spring 51. If now the ring valve should be closed, then the valve 38 would also be opened as already explained. This then would admit elastic fluid either from the pipe 40 through reducing valve 41, or from the first stage of the machine through pipe 42 and non-return valve 43, to the conduits 44 and 45 through which it would flow to the final stages of the machine and thence backward through the machine and through opening 22^a to the extraction stage and out through pipe 20. This will, therefore, provide a circulation of elastic fluid through the final stages of the machine and protect the wheels therein from overheating. Ordinarily the first stage pressure will be sufficiently high so that the elastic fluid may be taken from it, but if it is not, then it may be obtained directly from a primary source through pipe 40 and reducing valve 41.

It will be understood that when my invention is carried out in connection with a machine not provided with a stage valve, as the ring valve shown, then the valve 38 will be omitted, the flow of elastic fluid to the final stage or stages through conduits 44 and 45 being then wholly under the control of valve 39.

In accordance with the provisions of the patent statutes, I have described the principle of operation of my invention, together with the apparatus which I now consider to represent the best embodiment thereof; 130

but I desire to have it understood that the apparatus shown is only illustrative, and that the invention can be carried out by other means.

5. What I claim and desire to secure by Letters Patent of the United States, is:

1. The combination of a turbine having a conduit leading from an intermediate stage, a condenser into which the final stage exhausts, a stage valve controlling the passage of steam from such intermediate stage to the next lower stage, said stage valve being arranged so that it cannot entirely shut off the flow of elastic fluid through the turbine, 15 conduit means for supplying elastic fluid to a stage of the machine lower than such intermediate stage, and valve means which is under the control of the stage valve and the pressure existing in the final stage of 20 the machine for admitting elastic fluid through the conduit means to the final stage when the condenser vacuum is lost, and the stage valve is closed.

2. The combination of a turbine having a 25 conduit leading from an intermediate stage, a condenser into which the final stage exhausts, a stage valve controlling the passage of steam from such intermediate stage to the next lower stage, said stage valve being arranged so that it cannot entirely shut off the flow of elastic fluid through the turbine, conduit means for supplying elastic fluid to each stage of the machine lower than such intermediate stage, and valve 30 means which is under the control of the stage valve and the pressure existing in the final stage of the machine for admitting elastic fluid through the conduit means to the final stage when the condenser vacuum 35 is lost and the stage valve is closed.

3. The combination of a turbine having a conduit leading from an intermediate stage, a condenser into which the final stage exhausts, a stage valve controlling the passage 45 of steam from such intermediate stage to the next lower stage, said stage valve being arranged so that it cannot entirely shut off the flow of elastic fluid through the turbine, conduit means for supplying elastic fluid to one or more of the final stages of 50 the machine, and two valves in said conduit means, one of which is under the control of the stage valve and is opened when the stage valve is closed, and the other of 55 which is under the control of the pressure existing in the condenser and is opened

when said pressure reaches a predetermined high value for controlling the flow through said conduit means.

4. The combination of a turbine having a 60 conduit leading from an intermediate stage, a condenser into which the final stage exhausts, a stage valve controlling the passage of steam from such intermediate stage to the next lower stage, said stage valve being 65 arranged so that it cannot entirely shut off the flow of elastic fluid through the turbine, fluid actuated means responsive to the pressure of said intermediate stage for regulating the stage valve, a conduit connecting the first stage of the machine to the final stage, and valve means under the control of the stage valve and the pressure in the final stage for admitting elastic fluid 70 through said conduit when the stage valve is closed and the condenser vacuum is lost.

5. The combination with a turbine having a conduit leading from an intermediate stage and a condenser into which the final stage exhausts, of means for introducing 80 elastic fluid from an earlier stage of the machine into one or more of the lower stages of the machine when the condenser vacuum is lost, said means being controlled by the pressure of the condenser.

6. The combination with a turbine having a conduit leading from an intermediate stage and a condenser into which the final stage exhausts, of a pipe connecting an initial stage of the machine to one or more 90 of the final stages, a normally closed valve in said pipe, and means controlled by the pressure in the condenser for opening said valve.

7. The combination with a turbine having a 95 conduit leading from an intermediate stage and a condenser into which the final stage exhausts, of means controlled by the pressure in the condenser for introducing elastic fluid of a pressure higher than that 100 of said intermediate stage to one or more of the final stages of the machine when the condenser is shut down and the wheels in such final stages are running idle, whereby such elastic fluid may circulate backward 105 through the idle stages of the machine to prevent the wheels therein from overheating.

In witness whereof, I have hereunto set my hand this 19th day of June, 1916.

LOUIS C. LOEWENSTEIN.
